MASSAGER HOUSING

Alfred W. Madl, Mequon, and Ronald D. Raitnen, Milwaukee, Wis., assignors to John Oster Manufacturing Co., Milwaukee, Wis., a corporation of Wisconsin

Filed Aug. 1, 1966, Ser. No. 3,283

Term of patent 14 years

(Cl. D83—1)

FIG. 1 is a perspective view of an electric massager housing embodying our new design;

FIG. 2 is a side elevational view thereof;

FIG. 3 is a top plan view thereof; and

FIGS. 4 and 5 are front and rear elevational views respectively thereof.

The dominant features of our design reside in those portions shown in full lines.

The broken line portions illustrated in FIG. 1 of the drawing are shown for illustrative purposes only.

We claim:

The ornamental design for a massager housing, as shown and described.
